UNITED STATES PATENT OFFICE.

FRANK F. LANDIS, OF WAYNESBOROUGH, PENNSYLVANIA.

TRACTION-ENGINE BEARING.

SPECIFICATION forming part of Letters Patent No. 294,793, dated March 11, 1884.

Application filed December 9, 1882. (No model.)

To all whom it may concern:

Be it known that I, FRANK F. LANDIS, a citizen of the United States of America, residing at Waynesborough, in the county of Franklin and State of Pennsylvania, have invented 5 certain new and useful Improvements in Traction-Engine Bearings, of which the following is a specification.

My invention relates to certain improvements in bearings for traction-engines; and it 10 has for its object the provision of strong, simple, and semi-spherical bearings, which will permit of the oscillation of a shaft journaled therein, and be provided with suitable facilities for lubricating said journals; and, with 15 these main and other subsidiary objects in view, my invention consists in certain features of construction and combination hereinafter described, and specifically set forth in the 20 claims.

Referring to the drawings, Figure 1 is a side elevation of so much of a traction-engine embodying my invention as is necessary to a clear understanding of the same. Fig. 2 is a 25 horizontal section, taken on line $x-x$ of Fig. 1, of the bearings secured to the outside of the frame, to carry the main driving-gear. Fig. 3 is a vertical section of the same bearing, taken on line $y-y$ of Fig. 2. Fig. 4 is a vertical section of one of the bearings that rest upon the 30 axle and support the boiler. Figs. 5 and 6 are details in elevation and plan, respectively, of one of the axle-bearings stated immediately above.

Like letters refer to like parts in all the figures.

A represents a portion of the boiler; B, one of the frame-sills, formed of two parallel bars kept a short distance apart by thimbles and 40 bolted together to support the boiler; and C, the housing or side frame for the actuating-shafts and gearing. D represents the axle of the traction or ground wheels, all of which parts are fully described in other applications pending herewith, and therefore not described 45 in detail herein, as they are not essential to an embodiment of my present invention.

The weight of the portion of the boiler shown and of its adjacent mechanism is borne by the 50 axle D in suspension bearing-blocks $d-d'$ at

each side of the frame-work, resting on the axle. Passing through and depending from each block are two suspension-rods, d^2 , which extend through and below the sill B, and also pass through a cap, d^3 , coil-springs d^4 , and a 55 base-plate, d^5 , and at their lower ends are provided with heads d^6 and at their upper ends with nuts d^7 , which are tightened sufficiently to slightly compress the spring between the cap and base-plate. 60

By referring to Figs. 4, 5, and 6 it will be seen that each bearing comprises two parts—an inner bearing, d , and an outer bearing, d' —which constitute a ball-and-socket bearing, on account of the form given thereto. The inner 65 bearing, d , is on its lower face fitted to the journal of the axle D, while its upper face is convex longitudinally and circumferentially or spherically, to adapt it to fit a corresponding concave recess in the lower face of the 70 outer bearing, d' . Oil-ducts are provided in each, and they are enlarged at the outer surface of each bearing to hold a small supply, and a plate, e , is secured by the bolts d^2 over the upper bearing, and is perforated above its 75 oil-ducts. The wearing-surfaces of these bearings may be provided with entire or partial linings of Babbitt or other suitable metal, the usual means of securing the same therein being employed. 80

By the construction thus far described it is apparent that the inner surface of the bearing d is adapted to the rotation of the axle D, and its outer surface, in connection with the inner surface of the bearing d' , is adapted to the 85 oscillation of said shaft in a vertical plane both above and below its normally-horizontal position. Furthermore, the inner bearing, d , is extended to form a square shoulder, which bears against the usual shoulder provided on 90 the axle, and, being suitably supported in the housing or frame C, no appreciable movement longitudinal of the bearings upon the axle occurs.

Referring back to Figs. 1, 2, and 3, E represents a bridge-piece secured to the frame C by bolts F. This bridge is slotted centrally for the passage and the vertical oscillation 95 therein of the axle D, and is extended outwardly from the frame C to form a circular 100

journal, E', for the main gear-wheel, (not shown,) the latter being retained thereon by an annular flange, E². (See Fig. 2.)

Within the journal E' are formed oil-pockets G G, with supply-ducts g g at the top and delivering-ducts g' g' at the bottom. The annular flange or cap E² is secured to the end of the journal E' by bolts F in such a position as to close the ends of the oil-pockets. The cap E² is slotted in like manner as the bridge-piece and the journal E'. Upon this journal the usual traction-gear revolves, so that (in connection with connecting mechanism) power is conveyed from the motor to the traction-wheels.

This mechanism, being well known in the art and readily applicable by any mechanic conversant with this class of machinery, is not shown or further described herein.

The pockets G G may be filled with wool, cotton-waste, or sponge or other absorbent material, and thus a supply of oil may be retained within and gradually be fed from them to the frictional surfaces of the flange and the traction-gear rotating thereon.

Having described my invention and its operation, what I claim, and desire to secure by Letters Patent, is—

1. In a traction-engine, an axle-bearing block provided with an inner and an outer bearing-surface, the former adapted to the rotation of the axle, and the latter adapted to

its vertical oscillation, in combination with the sill B, formed of two parallel bars, suspension-rods between said bars, and springs under said sills, substantially as and for the purpose described. 35

2. The combination of the axle D, blocks d and d', suspension-rods d², sills B, caps d³ d⁵, and springs between said caps, substantially 40 as and for the purpose described.

3. In a traction-engine, the combination of the frame C and axle D with bridge E, having the journal E' and oil-pockets therein, substantially as and for the purpose described. 45

4. The combination, with the side frame, of the bridge-piece E, secured thereto, and having the journal E', with pockets G G, provided with the ducts g g', and the removable flange E², substantially as and for the purpose described. 50

5. In a traction-engine, the combination of the axle D, caps d³ d⁵, springs d⁴, rods d⁶, and bearings d d' with the slotted bridge E, having the annular journal E', substantially as and for the purpose described. 55

In testimony whereof I affix my signature, in presence of two witnesses, this 4th day of December, 1882.

FRANK F. LANDIS.
